UNITED STATES PATENT OFFICE.

THEODORE G. VOLGER, OF PARKRIDGE, NEW JERSEY, ASSIGNOR OF ONE-HALF TO FRANK O. MITTAG, OF SAME PLACE:

DESIGN FOR A RIBBON-SPool FOR TYPE-WRITING MACHINES.

SPECIFICATION forming part of Design No. 34,688, dated June 25, 1901.

Application filed May 25, 1901. Serial No. 61,975. Term of patent 14 years.

To all whom it may concern:

Be it known that I, THEODORE G. VOLGER, a citizen of the United States, residing at Parkridge, in the county of Bergen and State of New Jersey, have invented and produced a new and original Design for a Ribbon-Spool for Type-Writing Machines, of which the following is a specification, reference being had to the accompanying drawings, forming a part thereof, and in which—

Figure 1 is a face view of a ribbon-spool bearing and incorporating my design, and Fig. 2 is an edge view of same.

The leading feature of my design consists in the form and configuration of the ribbon-spool for type-writing machines, substantially as shown.

In the drawings, A designates the ribbon-spool as a whole, said spool comprising the hub B and the disks or flanges C, disposed at

the opposite ends of said hub B. The disks or flanges C are of ornamental configuration, as illustrated, and said disks or flanges are formed with the line of apertures D, while the edges of said disks or flanges are recessed, as at E, each recess E being disposed on a radial line intermediate two of the openings or apertures D, the whole being substantially as shown.

What I claim is—

The design for a ribbon-spool for type-writing machines, substantially as shown and described.

Signed at New York, in the county and State of New York, this 24th day of May, 1901.

THEODORE G. VOLGER.
